CLAIM

We claim the ornamental design for a housing for a biochemical analysis apparatus, as shown and described.

DESCRIPTION

FIG. 1 is an isometric view of a housing for a biochemical analysis apparatus with a fingerprint reader and cartridge slot on the sloped front surface, the "IntegenX" logo and a pentagonal raised panel encircling the logo, most of the back face and underside of the housing, and a seam that runs along the front face of the housing and down the sides of the housing rendered in broken lines to indicate unclaimed environmental structure.

FIG. 2 is a rear isometric view of the housing for a biochemical analysis apparatus of FIG. 1.

FIG. 3 is a front view of the housing for a biochemical analysis apparatus of FIG. 1.

FIG. 4 is a back view of the housing for a biochemical analysis apparatus of FIG. 1.

FIG. 5 is a bottom view of the housing for a biochemical analysis apparatus of FIG. 1.

FIG. 6 is a top view of the housing for a biochemical analysis apparatus of FIG. 1.

FIG. 7 is a left side view of the housing for a biochemical analysis apparatus of FIG. 1.

FIG. 8 is a right side view of the housing for a biochemical analysis apparatus of FIG. 1.

FIG. 9 is an isometric view of a housing for a biochemical analysis apparatus with the cartridge slot, "IntegenX" logo and surrounding pentagonal area, and most of the underside and back face of the housing rendered in broken lines to indicate unclaimed environmental structure.

FIG. 10 is a rear isometric view of the housing for a biochemical analysis apparatus of FIG. 33.

FIG. 11 is a front view of the housing for a biochemical analysis apparatus of FIG. 9.

FIG. 12 is a back view of the housing for a biochemical analysis apparatus of FIG. 9.

FIG. 13 is a bottom view of the housing for a biochemical analysis apparatus of FIG. 9.

FIG. 14 is a top view of the housing for a biochemical analysis apparatus of FIG. 9.

FIG. 15 is a left side view of the housing for a biochemical analysis apparatus of FIG. 9.

FIG. 16 is a right side view of the housing for a biochemical analysis apparatus of FIG. 9.

FIG. 17 is an isometric view of a housing for a biochemical analysis apparatus with the fingerprint reader, "IntegenX" logo and surrounding pentagonal area, and most of the underside and back face of the housing rendered in broken lines to indicate unclaimed environmental structure.

FIG. 18 is a rear isometric view of the housing for a biochemical analysis apparatus of FIG. 17.

FIG. 19 is a front view of the housing for a biochemical analysis apparatus of FIG. 17.

FIG. 20 is a back view of the housing for a biochemical analysis apparatus of FIG. 17.

FIG. 21 is a bottom view of the housing for a biochemical analysis apparatus of FIG. 17.

FIG. 22 is a top view of the housing for a biochemical analysis apparatus of FIG. 17.

FIG. 23 is a left side view of the housing for a biochemical analysis apparatus of FIG. 17.

FIG. 24 is a right side view of the housing for a biochemical analysis apparatus of FIG. 17.

FIG. 25 is an isometric view of a housing for a biochemical analysis apparatus with the fingerprint reader, cartridge slot, "IntegenX" logo and surrounding pentagonal area, and most of the underside and back face of the housing rendered in broken lines to indicate unclaimed environmental structure.

FIG. 26 is a rear isometric view of the housing for a biochemical analysis apparatus of FIG. 25.

FIG. 27 is a front view of the housing for a biochemical analysis apparatus of FIG. 25.

FIG. 28 is a back view of the housing for a biochemical analysis apparatus of FIG. 25.

FIG. 29 is a bottom view of the housing for a biochemical analysis apparatus of FIG. 25.

FIG. 30 is a top view of the housing for a biochemical analysis apparatus of FIG. 25.

FIG. 31 is a left side view of the housing for a biochemical analysis apparatus of FIG. 25; and,

FIG. 32 is a right side view of the housing for a biochemical analysis apparatus of FIG. 25.

FIGS. 1 through 32 are drawn to scale.

A housing for a biochemical analysis apparatus is shown in FIGS. 1-32.

Stipple shading is used throughout to show surface contouring and as an aid to determining boundaries between claimed subject matter and unclaimed environmental structure; unclaimed environmental structure is not shaded or hatched, whereas claimed subject matter is shaded or hatched. It is to be understood that the use of stipple shading does not convey any particular surface finish or surface texture, but is merely used as an aid to show surface contouring and the extent of claimed subject matter. In views where no natural boundary exists between claimed subject matter and unclaimed environmental structure, dashed-dotted-dashed lines are used to indicate such boundaries. For further clarity, tangent lines indicating smooth transitions between surfaces are depicted in grey dashed lines (short-short-long dashes). Broken lines, such as dashed and dotted lines, are used to indicate unclaimed environmental structure. In cases where broken lines are used to represent features on a shaded surface, such as is the case with the IntegenX logo, it is to be understood that the surface itself is still claimed but that the particular structures on that surface are unclaimed environmental structure.
